Ed. D. Davis.

Attorney

UNITED STATES PATENT OFFICE.

BRADFORD DAVIS, OF READING, PENNSYLVANIA.

FIREBACK FOR STOVES.

1,264,373.

Specification of Letters Patent. Patented Apr. 30, 1918.

Application filed July 16, 1917. Serial No. 180,693.

To all whom it may concern:

Be it known that I, BRADFORD DAVIS, a citizen of the United States, residing at Reading, in the county of Berks and State 5 of Pennsylvania, have invented certain new and useful Improvements in Firebacks for Stoves, of which the following is a specification.

This invention relates to improvements 10 in stoves, and it pertains more particularly to the construction of the firebrick, forming the wall between the fire box and the oven of an ordinary cooking stove.

In the use of firebrick heretofore, it has 15 generally been the practice to hold this brick in position by means of metal clips, engaging the upper edge of the firebrick.

In this construction, these metal clips or fingers will be destroyed by the flame from 20 the fire bed, and the firebrick become loose and fall away from the oven surface, thus reducing very materially the effectiveness of the oven.

In my present invention I have provided 25 a firebrick in which no portion of the metal used to retain the brick in position is exposed directly to the heat or flame from the fire box, but which will still securely engage and retain the firebrick in position.

30 Another feature of my invention is the ease with which the firebrick may be replaced and removed.

The invention is more fully described in 35 the following specification and clearly illustrated in the accompanying drawing, in which:—

Figure 1 is a sectional view of a portion of an ordinary cooking stove, taken through the line 1—1 of Fig. 4.

40 Fig. 2 is a front elevational view, partly broken away, of the firebrick, as viewed in the direction of the arrow in Fig. 1.

Fig. 3 is an end view of the firebrick, showing a portion of one of the side brick 45 members in engagement therewith.

Fig. 4 is a fragmentary plan view of section B and parts associated therewith.

Fig. 5 is an elevation of the inner face of 50 the firebrick section B, and Fig. 6 is a plan view thereof.

Referring to the drawing:—

The numeral 1 designates the fire box of an ordinary stove and 2 the front vertical wall of the oven against which the firebrick 55 3 is placed. This wall 2 is formed with a

longitudinal groove 4 in its base to receive a flange 5 on the firebrick members.

In the present instance I form this firebrick in two like sections, designated by the letters A and B.

These firebrick members are each formed with a lower flange 5, as stated, and also with an end flange 6 and these flanges 6 are adapted to enter notches 7 in the side firebrick members C.

The members A and B are each formed with a beveled edge 9 where they meet, at about the longitudinal center of the fire box, and each member is cut away on its inner or rear face, at the top, designated by the num- 60

eral 10. The numeral 11 designates a lug, formed on the face of the oven wall, and this lug registers with the cut away spaces 65

10 on the members A and B. Both the members A and B are provided at the upper 70

inner corner with an inlaid metal contact- 75

ing body 12, adapted to contact with the lug 11, to prevent wearing of the firebrick 80

at that point. The edges of the lug 11 are inclined, as is the inner edge of each of the 85

contact members 12, thus forming a dovetail 90

engagement between these parts, by means 95

of which the members A and B are held 100

against the oven wall. The cut away spaces 10 depend below the line of the lower edge 85

of the lug 11, and this cut away space ex- 90

10 extends about half way across the bevel edge 95

of the members A and B, as shown clearly 100

in Fig. 5, which shows the inner face of 105

the member A.

When it is desired to remove the members 110

A and B from engagement with the oven

wall, the member A is moved upward until

its lower flange is above the edge of the base

member groove 4, which movement will

bring the lower edge of the cut away space

10 against the lower edge of the lug 11; the

member A is then moved to the right, until

its side flange 6 is free from its engagement

with the side firebrick member C; the mem- 110

ber A may then be easily withdrawn, and

the other member B may be removed in the

same manner. In replacing them, the mem- 115

ber B is of course replaced first, on account

of the tapered inner edge 9.

It will be noted therefore that when the

two part firebrick is in position, the firebrick

alone is exposed to the fire, and that the

metal parts, while they will securely retain

the members in position, are protected from

115

burning, and, inasmuch as a fairly close fit at the meeting point of the beveled edges 9 may be secured, the result will be a substantially solid wall of firebrick; one that may 5 easily be removed and replaced, but also, one in which this removal and replacement is to a great extent overcome, inasmuch as the life of the firebrick is very materially increased, due to the fact that it is at all times 10 held securely in position against the oven wall, and the tendency to fall away therefrom overcome.

The contact members 12 are preferably embedded in the firebrick members, and are 15 flush with the surface thereof, both as to the inner face and the top, as shown clearly in Figs. 5 and 6.

It is evident that the parts described may be changed as to form and perhaps otherwise 20 modified without departing from the spirit of my invention, but what I claim and desire to secure by Letters Patent is:—

1. In a stove the combination of a fire box, an oven wall forming one vertical side of the firebox, said wall having a longitudinal groove in its base; a two part firebrick resting 25 against said wall; a lug formed on said wall at the top, said lug having inclined edges; each of the firebrick members hav-

ing a bottom and a side flange adapted to 30 hold it in position, a metal member inlaid in its body at the upper inner corner in dovetail engagement with said lug, and having a cut away space at its upper inner corner to permit the upward movement of the 35 firebrick while resting against the oven wall.

2. In a stove the combination of a fire box; an oven wall formed with a retaining groove in its base; a two-part firebrick in engagement with said groove; a lug on the oven 40 wall at the top to hold the upper ends of the firebrick members and a metal contacting member embedded in the firebrick members and in dovetail engagement with said lug. 45

3. In a firebrick for stoves, the combination of an oven wall formed with a bottom groove, and a lug at its upper end; with a two part firebrick having beveled meeting edges, flanges at their outer edges engaging 50 the side walls of the oven and flanges at their lower edges engaging said bottom groove, and inlaid metal contacting members in dovetailed engagement with the lug on the oven wall. 55

In testimony whereof I affix my signature.

BRADFORD DAVIS.
